UNITED STATES PATENT OFFICE.

FRANK L. SESSIONS, OF COLUMBUS, OHIO, ASSIGNEE TO THE JEFFREY MANUFACTURING COMPANY, A CORPORATION OF OHIO.

MINING-MACHINE.

1,143,144.

Specification of Letters Patent. Patented June 15, 1915.

Application filed February 16, 1909. Serial No. 478,201.

To all whom it may concern:

Be it known that I, FRANK L. SESSIONS, a citizen of the United States, residing at Columbus, in the county of Franklin and State of Ohio, have invented certain new and useful Improvements in Mining-Machines, of which the following is a specification, reference being had therein to the accompanying drawing.

This application relates to mining machines, and its object, generally stated, is to provide a machine having improved means for driving the cutters, for feeding the cutters against the coal, and for controlling the feed of the cutters.

In the accompanying drawings I show my invention embodied in a machine of the breast type, but, so far as certain features of the invention are concerned, it is applicable to machines of other types.

In the drawings Figure 1 is a plan view of the machine, Fig. 2 is a longitudinal vertical section on the line 2—2 of Fig. 1, the motor being shown in side elevation, Fig. 3 is a transverse section on the line 3—3 of Fig. 2, Fig. 4 is a transverse section on the line 4—4 of Fig. 2, Fig. 5 is an elevation of the left side of the front end of the machine, the rear part of the machine being broken away, Fig. 6 is a section on the line 6—6 of Fig. 1, Fig. 7 is a section on the line 7—7 of Fig. 1, Fig. 8 is a transverse section of the bed frame taken on the line 8—8 of Fig. 1, and Fig. 9 is a fragmentary section showing a detail of the construction of the bed frame and motor platform. Fig. 10 is a vertical section taken on the lines 10—10 in Fig. 1.

The machine is formed with two main parts, a bed frame and a carriage or cutter frame. The bed frame comprises side bars 1, 1 which, on their inner faces, are formed with channels or guideways for the carriage. These side bars 1, 1 are elevated somewhat above the ground being supported by transverse frame parts 2, 2, each of which comprises a horizontal cross bar 2^a and vertical bars 2^b, 2^c which carry the side bars 1, 1, the vertical bars 2^c, in the case of forward frame parts 2, having inward extensions 2^d which engage the said side bars 1. The transverse frame parts 2 rest upon shoes 3, 3, each of which has a part 3^a at the rear which is

substantially parallel to the longitudinal axis of the machine, and a part 3^b at the forward end which diverges. By having 55 the lower portion of the bed frame flared outwardly in this manner at the front end, ample room is given for the chain cutters and, at the same time, the latter are more or less surrounded by the bed frame so that 60 accidental contact of an operator with the cutters is prevented.

On the horizontal bars 2^a of the transverse frame parts 2 is mounted or secured a longitudinal bar or plate 4 which, in addition to 65 its function as a structural member, serves as one element of a brake mechanism which will presently be described. The front ends of the side bars 1 are united by a transverse bar 5 which is formed with or secured to a 70 transversely arranged pedestal 6.

The other main part of the machine, namely, the carriage or cutter frame which supports the cutting apparatus, comprises a rear platform 7, a depending bracket 8 adjustably secured to said platform, chain guides 9, 9 rigidly secured at their rear ends to the bracket 8, a front head 10 which rigidly unites the forward ends of the chain guides 9 and constitutes a transverse continuation thereof, and central guide and support 11 which is connected at its rear end to the bracket 8 and at its forward end is secured by rivets 12 to the front head 10. The carriage comprising these main parts is 85 slidably mounted upon the bed frame, the rear platform 7 having its side edges mounted in the channels or ways of the side bars 1, while the guide and support 11 engages guides 6^a, 6^b carried by the pedestal 6 of the 90 bed frame.

A cutter chain 13 is arranged to run in the guides formed by the guides 9, 9 and the front head 10. This chain passes over sprockets 14, 15 mounted in the front head 95 10, and at the rear end of the machine passes over a large sprocket wheel 16 which supports and drives it. The sprocket wheel 16 is carried by a vertical shaft 17 mounted in a bearing sleeve 18 formed with or secured to the platform 7. A spur gear 19 is mounted on the upper end of the shaft 17 and with it meshes a gear 20 which is mounted upon the upper end of a shaft 21.

This latter shaft is mounted in a bearing sleeve 22 which is also formed with or secured to the platform 7. The shaft 21 is driven by a sprocket wheel 23 mounted on its lower end, said sprocket wheel being driven in turn by a chain which will presently be described.

The bracket 8, as previously stated, is adjustably secured to the platform 7. The bracket is formed with lateral flanges 8^a, 8^b which engage guides or ways formed by plates 24, 24 bolted to the under side of the platform (see Fig. 3). The bracket is adjustably held in position by means of two screws 25, 25, the heads of which bear against depending lugs 26, 26 carried by the platform 7, and the threads of which engage nuts 27, 27 seated in sockets formed for them in the depending bracket part 8 (see Fig. 7). By means of the adjusting screws 25 that part of the cutter frame comprising the bracket 8, chain guides 9, 9, front head 10, and sprockets 14, 15 can be adjusted in relation to the rear platform 7, and thus the desired tension on the cutter chain may readily be secured.

Referring now to the devices which drive the sprocket wheel 23, 28 is an endless drive chain which engages said sprocket wheel 29 and is guided and supported in a frame 29 which in turn is supported on the central guide and support 11 of the carriage. This latter guide and support comprises a bottom horizontal plate 11^a and vertical side plates 11^b, 11^b, and, as previously stated, is secured at its rear end to the bracket 8 and at its front end to the front head 10. In the trough-like structure formed by the guide and support 11, the chain frame 29 is 40 slidably mounted. Said frame comprises a bottom plate 30 which rests upon the bottom plate 11^a of the central guide and support, chain guides 31, 31 which bear against the vertical walls 11^b of the central guide 45 and support, and flanges or plates 32, 32 which overlie the chain 28 to retain it in position. The parts of the chain frame 29 are rigidly secured together by means of rivets 33 as shown in Fig. 6.

50 At the forward end of the chain frame 29 is disposed a sprocket wheel 34 for the chain 28. This sprocket wheel is mounted upon a short shaft 35 which is supported at its lower end by the bottom plate 30 of the chain frame 29 and at its upper end by a transverse tie plate 36 which constitutes a rigid part of the frame 29. The bottom plate 11^a of the center guide and support is slotted at 37 to receive the lower end of 55 the shaft 35 and allow for a limited sliding movement of the frame 29 in the guide and support 11.

At its rear end the chain guide 29 is flexibly and adjustably connected to the depending bracket 8 by the following devices:

38 is a plate rigidly secured to the frame 29 and is provided with an upstanding lug 39 in which is mounted a screw 40. The head of this screw is formed with flanges 40^a, 40^a which are designed to receive the 70 upper end of a lever 41 which is mounted upon a pivot 42 carried by lugs 43, 43 extending forward from the bracket 8. A heavy coil spring 44 is interposed between the head of the screw 40 and the bracket 8, 75 the latter being provided with a socket to receive the said spring. The lever 41 has a rearwardly extending arm 41^a which carries a friction face or shoe 41^b. This friction shoe of the lever is disposed adjacent the 80 upper face of the longitudinally arranged plate or bar 4 of the bed frame and is adapted to be brought into frictional engagement with said bar when the chain frame 29 is moved in relation to the bracket 8, as will be fully explained in the description which is to follow. It is clear that when the chain 28 is driven so as to cause the rotation of the sprocket wheel 23, the cutter chain will be driven through the 90 gearing mounted on the rear platform, but one of the important objects of my invention is to utilize the chain 28 for effecting the movement of the carriage as well as for driving the cutter chain in its guides. This 95 I accomplish by the use of motor mechanism arranged and constructed as follows.

45 is an electric motor which comprises an external field frame 45^a, and an armature mounted on a shaft arranged horizontally with a commutator at its rear end and with a bevel pinion 46 at its front end. It is unnecessary here to describe in detail the working parts of the motor as my invention is not restricted to any particular form 100 of motor mechanism. The motor or engine, however, should be constructed so that it may be moved somewhat transversely of the machine for a purpose to be hereinafter described.

The motor is mounted upon a platform which comprises a horizontal plate 47 which is supported by vertical side plates 48, 48, which are slidably supported at their lower edges upon the side bars 1, 1 of the bed 115 frame. The side plates 48 carry depending flanges or plates 49, 49 which are slotted at 49^a, 49^a to receive bolts 50, 50 rigidly secured to the side bars 1, 1 of the bed frame. This bolt and slot construction provides for 120 a limited sliding movement of the platform and motor upon the bed frame.

The platform and motor are normally held in the forward position shown in the drawings by means of heavy coil springs 51, 51 125 which are interposed between the platform, at either side thereof, and standards 52, 52 which are rigidly secured to the side bars of the bed frame. A screw 53 is adjustably mounted in each of the standards 52 and car-

ries an enlargement to receive the rear end of spring 51. By turning the screws 53, the tension of the springs 51 may be varied as desired.

5 The motor 45 is adjustably mounted on the supporting platform, the field frame 45^a of the motor being formed with a cylindrical boss or pivot 54 which fits an aperture 55 formed in the plate 47 of the platform. The 10 motor is held down by means of clips or guides 56 and 57 which are bolted to the platform, the clips 56 engaging the plate-like extensions 59, 59 of the motor frame, while the clips 57 engage the horizontal part 15 of a bracket 60 which is bolted to the front end of the motor frame. The edges of the extensions 59 and of the bracket 60 are formed concentric with the pivot 54 so as to permit a limited swinging of the motor on 20 said pivot. The bevel pinion 46 of the motor meshes with a bevel gear 61 which is secured to the upper end of a shaft 62 mounted in a bearing sleeve 60^a of the bracket 60. A web 60^b extends between the horizontal 25 part of the bracket and the sleeve 60^a to give strength and stiffness. The sleeve 60^a and web 60^b depend through an aperture 47^a in the platform, said aperture being of a size and shape to permit a limited lateral movement 30 of the sleeve 60^a. On the lower end of the shaft 62 is mounted a sprocket wheel 63 which is disposed in position to engage the endless drive chain 28, and by swinging the motor and with it the bracket 60 and 35 sprocket wheel 63, the latter may be made to operatively engage either the left or the right run of the chain 28.

For swinging the motor, I provide a worm rack or segment 64, which is secured to the 40 field frame of the motor at one side, and a worm 65 which engages said segment. This worm is secured to a shaft 66 which is mounted in bearing standards 67, 68, which rise from the side of the motor platform, as 45 is clearly shown in Fig. 5. 69 is a hand wheel on the rear end of the shaft 66, by means of which the latter may be conveniently turned to swing the motor from left to right, or vice versa.

50 It will now be clear that if the motor were started when in the position shown in Fig. 1, that is with the sprocket wheel 63 engaging the left run of chain 28, the latter will be moved, and as it passes over the idle sprocket 34 and the rear sprocket 23, the latter will be driven in a direction to cause the forward movement of the cutter chain. It is obvious that if there were no force opposing said cutter chain, the only effect of the motor 55 would be to cause the chain to travel around the cutter frame in its guides. But even, when the chain runs idle, that is to say, before engaging the coal, the friction which results from the movement of the chain in 60 its guides constitutes such a force in oppo-

sition to its movement and, therefore, the rotation of the sprocket wheel 63 in engagement with chain 28 tends not only to move the cutter chain in its guides but also to bodily advance the carriage, the chain 28 or, 70 to speak more accurately, the left run thereof acting as a rack. As the force opposing the travel of the cutter chain increases, it is clear that the force tending to advance the carriage also increases and thus an automatic 75 feed of the cutters is effected. This simple automatic feed would perhaps operate satisfactorily under some conditions, but ordinarily in the operation of machines of this sort, the cutters encounter coal or foreign 80 substances of varying degrees of hardness, and as the force tending to advance the carriage increases with the resistance met by the cutters, it is necessary to provide additional means for controlling the feed of the carriage in order to prevent the stalling of the machine when unusually hard substances are 85 encountered. I shall now describe a controlling means of this character which is arranged to be operated either automatically, 90 or by the operator.

70 is a vertical shaft mounted in suitable bearings carried by the cross bar 5 and pedestal 6 of the bed frame. 71 is an eccentric arranged on said shaft 70 in position to 95 engage one side of the central guide and support 11 of the carriage. The upper end of shaft 70 carries a lever arm 72 which is connected to a link 73 extending toward the rear and provided at its rear end with a 100 handle 74. This link 73 passes through a guide standard 75 rigidly secured to the motor platform, and carries a collar 76 arranged to be engaged by the standard 75. 77 is a 105 pawl pivotally mounted on the standard 75 and arranged to engage a shoulder 78 on the link 73. The operator, by grasping the handle 74, may draw the link back and cause the eccentric to engage the guide 11 of the carriage, and thus oppose the advance of the 110 carriage. However, this will be accomplished automatically with the construction which has been described, for it is clear that when the force tending to advance the carriage increases to a certain extent, the tension of the springs 51 will be overcome and the motor and its supporting platform will slide backward on the bed frame. During this movement the link 73 is drawn backward by reason of the engagement of the 115 standard 75 with the collar 76 of the link, and the braking action of the eccentric 71 is thus effected automatically and the feed of the carriage is retarded.

Referring now to the operation as a whole, let it be assumed that the machine is brought into the mine room where the coal is to be undercut. The machine is first positioned adjacent the face of the coal, and the bed frame is secured by jacks in the usual man- 120 125 130

ner. Then, with the motor in the position shown in Fig. 1, so as to bring the sprocket wheel 63 into engagement with the left run of the drive chain 28, the operator starts the motor. The sprocket 63 is turned in a clockwise direction thus moving the left run of the chain 28 forward and driving the sprocket 23 which, through the gears 20 and 19 drives the main sprocket wheel 16 in an anti-clockwise direction so as to move the cutters forward. The resistance offered to the movement of the cutters in the form either of friction in the chain guides or of such friction combined with the resistance of the coal, in case the cutters have been initially placed in contact with the face of the coal, will cause the tension exerted on the left run of the chain 28 to exert a force on the carriage of the machine, tending to move the cutter frame bodily forward against the coal. The chain 28 acting thus is in the nature of a traveling rack and serves to simultaneously move the cutter chain in its guides, and to bodily advance the cutter frame against the coal.

The continued operation of the motor causes the gradual feeding forward of the carriage, thus undercutting the coal in the well known way in which such operation is effected by breast machines. If at any time during the advance of the carriage, the cutters should encounter substances of unusual hardness so that resistance to the movement of the cutters were gradually increased, the force tending to draw the carriage forward would correspondingly increase, and might increase to such an extent as to stall the motor, or exceed the limit at which the machine could be operated with safety. This tendency, however, is overcome and such a result is prevented by the automatic operation of the eccentric brake. That is to say, when the resistance to the cutters becomes so great that the tension in the chain 28 is sufficient to overcome the springs 51, 51, the motor platform is caused to slide backward somewhat on the bed frame, thus bringing the eccentric brake 71 into operation in the manner hereinbefore described. The feed of the cutter frame is thus retarded for a time until the cutters have freed themselves somewhat and the tension in the chain 28 has diminished. The springs 51 then cause the motor platform to move forward again to its normal position, which forward movement causes the unlocking of the eccentric brake 71 through the action of the pawl 77 which engages the link 73. The advance of the carriage thus continues, the eccentric brake 71 being brought into action automatically from time to time, according to the nature of the coal or other substance being encountered by the cutters. It will, of course, be understood that the

brake 71 can be manually actuated by the operator at any time, if that becomes desirable or necessary in handling the machine.

When the carriage has been fed forward to the limit of its travel and the cut completed, the operator effects the retraction of the carriage by turning the hand wheel 69 so as to swing the motor bodily upon its pivot 54. This causes the sprocket wheel 63 to be carried out of engagement with the left run and into engagement with the right run of the drive chain 28. Then, as the rotation of the motor continues in the same direction, the chain 28 continues to be driven in the same direction, but the tension in that part of the right run of the chain 28 between the sprocket wheel 63 and the sprocket wheel 34, as well as the tension in the left run of the chain 28, tends to draw the sprocket wheel 37 bodily backward. As this sprocket wheel is mounted in the chain frame 29, which is slidably supported in the central guide and support 11, it is clear that the tension in the two runs of the chain 28 will exert a backward thrust on the chain frame 29. Said chain frame is connected to the rear platform bracket 8 by the screw 40, lever 41 and coil spring 44 as previously described, and the effect of the backward thrust on the chain frame 29 is, therefore, to force the rear platform, and with it the entire carriage backward. If, however, the retraction of the carriage should encounter any unusual resistance, such, for example, as would result from the falling of coal on the cutters, the tension of the spring 44 would be overcome by the thrust of the chain frame 29, and the latter would have a corresponding sliding movement in the support 11. Such movement would cause the swinging of the lever 41, which, it will be recalled, is mounted on the platform bracket 8, so as to bring the brake shoe 41^b into engagement with the longitudinal bar 4 of the bed frame. The retraction of the carriage would thus be stopped, until the obstruction were removed, and any undue straining or breakage of the machine prevented.

From a consideration of the construction which has been described, it will be apparent that the amount of force or pressure exerted by the motor to drive the cutting devices will have a certain definite predetermined relationship to the amount of force or pressure exerted by the motor to feed the carriage forward. In using the terms "force" or "pressure," I desire to clearly distinguish from the meanings expressed by other terms such as "power" or "energy." As stated above, the cutter driving force and the carriage feeding force will be definitely proportioned to each other in a machine constructed in accordance with my invention; but the

amounts of power received by the cutting devices and by the carriage, respectively, will vary greatly relatively to each other in accordance with the speeds at which the conditions of use permit the two devices to travel. If the resistance to feeding is great, the rate of feeding is correspondingly slow and the actual power transmitted to the carriage is very small; but the amount of force or pressure transmitted to the carriage to feed it remains definitely proportioned to the amount of pressure transmitted to the cutting devices. And if the resistance to feeding is very small, the rate of feeding is correspondingly great and the amount of power expended in feeding the carriage is relatively large; but the force applied to feeding the carriage remains, as before, definitely proportioned to the force transmitted to drive the cutting devices.

It will now be understood that the machine which I have produced not only effects the automatic feed of the carriage, but also automatically controls the feed according to the character of the coal or other substances which the cutters engage. In fact, the power transmitting mechanism which I have provided is a differential one which serves to transmit force in definite predetermined proportions to the cutters to drive them and to the carriage to feed it forward. The amount of the carriage feeding force is dependent upon the resistance offered to the cutters and the amount of force transmitted to the cutters is dependent upon the resistance offered to the forward feeding of the carriage. Furthermore, this result is secured with mechanism that is remarkably simple. I dispose entirely with all of the ordinary feeding apparatus, such as racks and pinions, shafting and gearing to drive them, which parts, as ordinarily used, are absolutely positive in their action and in no wise automatically accommodating in relation to the resistance encountered by the cutters. These feeding mechanisms, as ordinarily used, comprise feed worms, gearing, shafts, clutches, etc., together with many details incident thereto, and are responsible for a large part of the labor and expense incident to the manufacture of such machines.

Many of the detail features, both of the construction and of the operation of my machine, may be varied without departing from my invention. It is clear, for example, that the carriage might be retracted by reversing the motor and maintaining the sprocket wheel 62 in engagement with the left run of the chain 28. This method of operation, however, would cause the cutters to move backward during the retraction of the carriage, and as this is usually not desirable, I prefer to retract the carriage by swinging the motor so as to bring the sprocket 63 into

engagement with the right run of the drive 65 chain 28, the motor continuing to run in the same direction.

The subject-matter of this application is, in many respects, like that of my forfeited application, Serial No. 138,159, filed January 7, 1903.

What I claim is:

1. In a mining machine, the combination of a bed frame, a carriage movable forward and back thereon, cutters mounted on the said carriage, a motor, and a train of power transmitting elements connecting said motor to the cutters, one of said train of elements being mounted on the bed frame, another on the carriage and one of said elements being arranged both to transmit power to the said cutters and to move the carriage along the bed frame.

2. In a mining machine, the combination of a bed frame, a carriage movable forward and back thereon, a power actuated driving member mounted on one of said parts, an endless chain operatively mounted on the other of said parts and arranged to operate both as a carriage feeding element and as a cutter actuating element, and cutters actuated by said chain.

3. In a mining machine, the combination of a bed frame, a carriage movable forward and back thereon, a cutting apparatus mounted on said carriage, a motor, an endless chain mounted on said carriage and arranged to operate both as a carriage feeding element and as a power transmitting element, power transmitting devices interposed between said endless chain and said motor, and power transmitting devices interposed between said endless chain and said cutting apparatus.

4. In a mining machine, the combination of the bed-frame, the endless chain carrying cutters, the endless chain for advancing the cutters bodily along the bed, and means connecting the two chains for transmitting the power from the latter to the former, substantially as set forth.

5. In a mining machine, the combination of the bed-frame, the carriage, the cutting apparatus on the carriage, a power wheel on the bed frame, a carriage moving mechanism on the carriage, actuated by the said power wheel, and means connecting the cutting apparatus to the carriage-moving mechanism, substantially as set forth.

6. In a mining machine, the combination of the bed-frame, the carriage, the cutting apparatus on the carriage, the endless movable chain mounted longitudinally of the carriage, means for connecting the cutting apparatus to said chain and adapted to transmit variable loads from the cutting apparatus to the chain, and the driving devices for the chain, substantially as set forth.

7. In a mining machine, the combination

- of the bed-frame, the carriage, the cutting apparatus on the carriage, the carriage-moving mechanism on the carriage, means connecting the carriage-moving mechanism to the cutting apparatus, and a continuously speeded driving mechanism connected to the carriage-moving mechanism and transmitting power therethrough to the cutting apparatus, substantially as set forth. 5
8. In a mining machine, the combination of the bed, the carriage, the cutting apparatus on the carriage, the carriage-moving mechanism, power transmitting devices connecting the carriage-moving mechanism with the cutting apparatus, and a continuously acting driving mechanism primarily actuating the carriage-moving mechanism and transmitting power therethrough to the cutting apparatus, substantially as set forth. 10
9. In a mining machine, the combination of a bed-frame, a carriage movably mounted on said frame, a power actuated driving member mounted on one of the said parts, transmission mechanism operatively mounted on the other of the said parts, and cutters arranged to be actuated by the transmission mechanism, the said driving member being arranged to apply force to the transmission mechanism in the general direction of the carriage movement, whereby said transmission mechanism is effective, both to drive the cutters and to move the carriage. 15
10. In a mining machine, the combination of a bed-frame, a carriage movable forward and back thereon, a power actuated driving member mounted on one of the said parts, an endless chain operatively mounted on the other of the said parts, and cutters arranged to be actuated by said chain, the said driving member being arranged to apply force to said chain in the general direction of the carriage movement, whereby said chain is effective, both to drive the cutters and to move the carriage. 20
11. In a mining machine, the combination of a bed-frame, a carriage movable forward and back thereon, a power actuated driving member mounted on the bed frame, an endless drive chain operatively mounted on the carriage longitudinally thereof, a cutter chain operatively mounted on the carriage, and transmission devices between the drive chain and said cutter chain, the said driving member being arranged to apply force to the drive chain in the general direction of the carriage movement, whereby said chain is effective both to drive the cutters and to move the carriage. 25
12. In a mining machine, the combination of a bed frame, a carriage movable forward and back thereon, a power actuated driving member movably mounted on the bed frame, an endless drive chain operatively mounted on the carriage with two runs arranged longitudinally thereof, a cutter chain opera-
- tively mounted on the carriage, and transmission devices between the drive chain and said cutter chain, the said driving member being movable into operative engagement with either of said longitudinal runs of the drive chain, whereby said chain is effective to drive the cutters and to both advance and retract the carriage. 30
13. In a mining machine, the combination of a stationary frame, a cutter frame movably mounted on said stationary frame, cutters operatively mounted on the cutter frame, and feed mechanism for the cutter frame comprising a power actuated driving member mounted on one of the said frames, and a driven member normally held against bodily movement relative to the other frame, said driven member being arranged to transmit power from the power actuated member to the cutters. 35
14. In a mining machine, the combination of the bed, the carriage, the cutting apparatus on the carriage, the carriage-moving mechanism, comprising an endless chain on the carriage, means connecting said endless chain to the cutting apparatus, and an automatic brake adapted to be brought into action upon the increase of tension of the chain to resist the movement of the carriage, substantially as set forth. 40
15. In a mining machine, the combination of a bed frame, a carriage movable forward and back thereon, cutting apparatus mounted on the said carriage, an endless chain mounted on said carriage and arranged both to operate as a carriage feed element and for transmitting power to said cutting apparatus, a motor, power transmitting mechanism connecting said motor with said endless chain on the carriage, power transmitting mechanism connecting said chain with said cutting apparatus, and means for controlling the tension on the active run of said endless chain. 45
16. In a mining machine, the combination of a bed frame, a carriage movable forward and back thereon, a power actuated driving member mounted on one of the said parts, an endless chain operatively mounted upon the other of said parts and arranged to operate both as a carriage feeding element and as a cutter actuating element, cutters actuated by said chain, and an automatic brake adapted to be brought into action upon the increase of tension of the chain to resist the movement of the carriage. 50
17. In a mining machine, the combination of a stationary frame, a cutter frame movably mounted on said stationary frame, cutters operatively mounted on the cutter frame, a motor, a power transmitting mechanism interposed between the motor and the cutters to drive them and the cutter frame to feed it forward or backward, and automatically acting means supplemental to the 55
- 120
- 125
- 130

said power transmitting mechanism for controlling the feeding of the cutter frame, the said automatically acting means being controlled by the variation of the driving force 5 applied to the cutters.

18. In a mining machine, the combination of a stationary frame, a cutter frame movably mounted on said stationary frame, cutters operatively mounted on the cutter frame, a motor, power transmitting mechanism interposed between the motor and the cutters to drive them and the cutter frame to feed it forward and backward, and a 10 brake device supplemental to the power transmitting mechanism for controlling the movement of the cutter frame.

19. In a mining machine, the combination of a bed frame, a carriage movable forward and back thereon, a power actuated driving 20 member mounted on one of the said parts, an endless chain operatively mounted on the other of the said parts and arranged to operate both as a carriage feeding element and as a cutter actuating element, cutters actuated by said chain, and a brake device for controlling the movement of the carriage.

20. In a mining machine, the combination of a bed frame, a carriage movable forward and back thereon, a power actuated driving 30 member mounted on one of the said parts, an endless chain operatively mounted on the other of the said parts and arranged to operate both as a carriage feeding element and as a cutter actuating element, cutters actuated by said chain, and means controlled by the variation of the tension in the drive chain for automatically controlling the movement of the carriage.

21. In a mining machine, the combination 40 of a bed frame, a carriage movable forward and back thereon, a power actuated driving member mounted on one of the said parts, an endless chain operatively mounted on the other of the said parts and arranged to operate both as a carriage feeding element and as a cutter actuating element, cutters actuated by said chain, and automatic devices for controlling the forward movement and the backward movement of the carriage.

50 22. In a mining machine, the combination of a bed frame, a carriage movable forward and back thereon, a power actuated driving member mounted on one of the said parts, an endless chain operatively mounted on the other of the said parts and arranged to operate both as a carriage feeding element and as a cutter actuating element, cutters actuated by said chain, and automatic devices controlled by the variation of the tension in the drive chain for controlling the forward movement and the backward movement of the carriage.

60 23. In a mining machine, the combination of a stationary frame, a cutter frame movably mounted on said stationary frame, cut-

ters operatively mounted on the cutter frame, a motor, power transmitting mechanism interposed between the motor and the cutters to drive them and the carriage to feed it forward and backward, and automatically acting devices supplemental to the power transmitting mechanism and operable in all positions of the cutter frame for controlling the forward movement and the backward movement thereof. 70

24. In a mining machine, the combination of a bed frame, a carriage movable forward and backward thereon, cutter mechanism mounted on the carriage, a motor, and power mechanism interposed between the motor on the one hand and the cutter mechanism and the carriage on the other hand for differentially transmitting the force of the motor in predetermined proportions to the said cutter mechanism to drive it and to the said carriage to feed it forward. 75

25. In a mining machine, the combination of a bed frame, a carriage movable forward and backward thereon, cutter mechanism mounted on the carriage, a motor, power 90 mechanism interposed between the motor on the one hand and the cutter mechanism and the carriage on the other hand for differentially transmitting the force of the motor in predetermined proportions to the said cutter mechanism to drive it and to the said carriage to feed it forward, a brake for resisting the forward movement of the carriage, and manually controllable means for applying and releasing the brake. 95

26. In a mining machine, the combination of a bed frame, a carriage movable forward and backward thereon, cutter mechanism mounted on the carriage, a motor, power mechanism interposed between the motor on the one hand and the cutter mechanism and the carriage on the other hand for differentially transmitting the force of the motor in predetermined proportions to the said cutter mechanism to drive it and to the said carriage to feed it forward, a brake for resisting the forward movement of the carriage, and automatically acting means for applying the brake upon the transmission to the carriage of a predetermined feeding 100 force. 105

27. In a mining machine, the combination of a bed frame, a carriage movable forward and backward thereon, cutter mechanism mounted on the carriage, a longitudinally extending endless drive chain on the carriage operatively connected with the cutter mechanism, a motor on the bed frame, a sprocket wheel meshing with the drive chain and operatively connected with the motor, the wheel being movable longitudinally of the bed frame, means for resisting the longitudinal movement of the wheel, and means dependent upon the movement of the sprocket wheel against the influence of the 110 120 125 130

said resisting means for retarding the movement of the carriage.

28. In a mining machine, the combination of a bed frame, a carriage movable forward and backward thereon, cutter mechanism mounted on the carriage, a longitudinally extending endless drive chain on the carriage operatively connected with the cutter mechanism, a motor longitudinally movable on the bed frame, means for resisting the longitudinal movement of the motor, a sprocket wheel movable with the motor and meshing with the drive chain, and means dependent upon the movement of the motor against the influence of the said resisting means for retarding the movement of the carriage.

29. In a mining machine, the combination of a bed frame, a carriage movable forward and backward thereon, cutter mechanism mounted on the carriage, a longitudinally extending endless drive chain on the carriage operatively connected with the cutter mechanism, a motor, a sprocket wheel positioned between the runs of the drive chain and operatively connected with the motor, and means for moving the motor and the sprocket wheel bodily to bring the wheel into mesh with either chain run, whereby the re-action of the chain on its guides may feed the carriage either forward or backward as desired.

30. In a mining machine, the combination of a bed frame, a carriage movable forward and backward thereon, cutter mechanism mounted on the carriage, a longitudinally extending endless drive chain on the carriage operatively connected with the cutter mechanism, a motor movable longitudinally of the bed frame, means for resisting the longitudinal movement of the motor, a sprocket wheel positioned between the runs of the drive chain and operatively connected with the motor, means for moving the motor and the sprocket wheel bodily to bring the wheel into mesh with either chain run, whereby the re-action of the chain on its guides may feed the carriage either forward or backward as desired, and means dependent upon the movement of the motor against the influence of the said resisting means for retarding the movement of the carriage.

31. In a mining machine, the combination of a bed frame, a cutter frame movable forward and backward on the bed frame, power driven cutter mechanism on the cutter frame, two parallel longitudinal feed elements on the cutter frame, a sprocket wheel on the bed frame and positioned between the two feed elements, a motor connected with the sprocket wheel for driving it always in the

same direction, and means for moving the sprocket wheel into mesh with either feed element to feed the cutter frame in either direction as desired.

32. In a mining machine, the combination of two frames one movable longitudinally with respect to the other, power driven cutter mechanism on the movable frame, two parallel longitudinal feed elements on one of the said frames, a sprocket wheel on the other of said frames positioned between the two said feed elements, a motor connected with the sprocket wheel for driving it always in the same direction, and means for moving the sprocket wheel into mesh with either feed element to feed the movable frame in either direction as desired.

33. In a mining machine, the combination of a cutter frame, a cutter mechanism on the frame, a motor, and power mechanism interposed between the motor on the one hand and the cutter mechanism and cutter frame on the other hand for differentially transmitting the force of the motor in predetermined proportions to the cutter mechanism to drive it and to the cutter frame to move it bodily.

34. In a mining machine, the combination of a cutter frame, a cutter mechanism on the frame, a motor, power mechanism interposed between the motor on the one hand and the cutter mechanism and cutter frame on the other hand for differentially transmitting the force of the motor in predetermined proportions to the cutter mechanism to drive it and to the cutter frame to move it bodily, means for retarding the bodily movement of the cutter frame, and manually controllable means for applying and releasing the retarding means.

35. In a mining machine, the combination of a cutter frame, a cutter mechanism on the frame, a motor, power mechanism interposed between the motor on the one hand and the cutter mechanism and cutter frame on the other hand for differentially transmitting the force of the motor in predetermined proportions to the cutter mechanism to drive it and to the cutter frame to move it bodily, means for retarding the bodily movement of the cutter frame, and automatically acting means for applying the retarding means upon the transmission to the cutter frame of a predetermined feeding force.

In testimony whereof I affix my signature, in presence of two witnesses.

FRANK L. SESSIONS.
